ROAD GUARD CONSTRUCTION

Firman L. Carswell and Otto W. Schmidt, Kansas City, Mo., assignors to Republic Steel Corporation, Youngstown, Ohio, a corporation of New Jersey

Continuation of applications Serial No. 575,852, November 18, 1931, and Serial No. 578,068, November 21, 1931. This application March 23, 1932, Serial No. 600,720

12 Claims. (Cl. 256—13.1)

This invention relates to road guard construction, and more particularly to a guard rail consisting of a plurality of rail members secured in overlapping end-to-end relation, and resiliently supported on post members placed along a highway.

Various means have been employed in the past to prevent a vehicle from leaving the highway. These means have taken the form of ordinary 10 wooden rail fences, strands of cable, guards made of wire mesh and metal rails of various types variously mounted. In the case of wooden fences little or no protection was afforded. The rails under impact would often splinter and break, thus presenting a greater menace to life than no fence at all. In the case of strands of cable, although of sufficient strength to prevent the vehicle from leaving the road the tendency was for the impacting vehicle to be guided by the 15 cable into a pocket adjacent the concrete post, supporting the cable, thus resulting in extensive damage to the vehicle. Similar objections accompany the use of wire mesh, but in addition, distortion of the wire mesh was permanent and necessitated the replacement of the entire stretch of fencing.

The metal rail guards have been variously devised, but have not come into general use, due, no doubt, to certain inherent deficiencies. Flat 30 metal sheets have been tried, but found to be unsatisfactory because of their tendency to twist and let a vehicle run under them as well as their ready tendency to take a permanent set in a distorted position. In certain instances the individual metal sheets or rails have each been tensioned by resilient connections to the supporting posts. An impact against one such rail was absorbed almost entirely by such rail with resultant injury to or virtual destruction of the rail or its 35 mountings. In certain cases where the rails were secured together so as to transmit impact stresses the rail was not anchored at the opposite ends and hence the device was largely ineffective.

As the result of many experiments and much investigational work we have devised a road guard construction which has successfully met the most exacting requirements and tests in use, which embodies principles and features not present in prior road guards, and which is simple and cheap to make, erect and repair.

The embodiment of the present invention disclosed herein consists generally of a plurality of upright supporting posts, a rail consisting of 55 metal members adjustably secured to each other

in overlapping or telescoping relation and tensioned as an entirety and anchored at each end, and resilient mountings to secure the rail to the posts. The posts may be of any desired form, shape and material so long as they afford adequate support for the rail. The resilient mountings are adjustable lengthwise of the rail to align readily with posts which are not set exactly in proper predetermined positions and are so constructed as to permit considerable lateral movement of the rail relative to the posts while strongly resisting any twisting or vertical movements of the rail. The mountings extend out from the posts far enough for a vehicle wheel in engagement with the rail to miss the post entirely. The rail is tensioned as an entirety and is anchored at each end so that an impact force is distributed throughout the rail and to all the mounting springs with the result that a tremendous force can be absorbed and yet the device will be able to spring back to its normal position quickly enough and with force sufficient in many cases to throw the impacting vehicle clear of the rail. The rail is rigid and highly resistant to permanent deformation because of its corrugated shape, thus providing great strength for a given metal thickness. The corrugations make the rail readily visible at all times because of the tendency to form lengthwise parallel bright and dark lines or areas due to the different angles at which light is reflected from the tops and bottoms of the corrugations. No marker, such as colored reflectors and the like are needed for this reason. Moreover, the corrugations afford the minimum amount of frictional resistance to an auto tire or other part and hence a vehicle after striking the rail may continue along in engagement with it and be easier to steer away from the rail than where the friction is greater as the case of a flat rail. The entire device can be readily erected or assembled, and damaged or broken parts can be readily replaced.

This application is a continuation of our pending applications, Serial No. 578,068, filed November 21, 1931 and Serial No. 575,852, filed November 18, 1931.

Our invention will be better understood from the following detailed description of one embodiment thereof wherein similar characters of reference designate corresponding parts and where-

partly in section of the device of Figure 1 taken near a supporting post;

Figure 3 is a fragmentary rear side view illustrating the means for securing adjacent rail members together and taken on line 3-3 of Figure 2;

Figure 4 is a fragmentary sectional view taken on line 4-4 of Figure 2;

Figure 5 is a fragmentary view illustrating the anchoring means at the end of the rail.

The guard rail A consists of a plurality of metal rail members 1 corrugated lengthwise as shown, and secured to each other in overlapping and preferably telescoping relation, as shown in Figure 3, the edges of each rail member 1 being rolled over to present a curved or rounded edge surface. Adjacent members 1 are secured together as by bolts 2 carried by one member and extending through elongated slots 3 in the other member. A bracket 4 secured as by rivets 5 to one member 1 affords anchorage for the bent ends of tensioning and adjusting bolts or tie rods 6, which bolts extend past a somewhat similar bracket 1 secured to the adjacent rail member as by rivets 8. Nuts 9 on the bolts 6 serve to adjust to a limited extent the brackets 4 and 7 relative to each other and to tension the rail A at the joints of the members 1. These adjusting means, as shown in Fig. 3, are disposed wholly to one side of the point of overlap of the rails, which point of overlap is defined by the end of one rail into which the other rail telescopes. In other words the adjusting means do not span the space between the untelescoped ends of the rails but on the contrary are located on the rear side of the rail into which a cooperating rail is telescoped. The rail A is anchored at each end as by a bracket 10, secured to the end member 1, a link 11 co-operating therewith, a link 12 including a turnbuckle and a deadman (not shown). The turnbuckles apply tension to the rail A as an entirety and this tension may be supplemented by bolts 6.

The mounting for the rail A comprises the bracket 7, a second bracket 13 secured to the supporting post 14 as by a bolt 15 and interconnecting bolts 16 with which spacing compression springs 17 are associated. The bracket 7 has a loose sliding fit in the arms of bracket 13 but lateral relative movement of these brackets is resisted by one or both of the springs 17. If a force is applied to the lower part of the rail A it is resisted by the lower springs 17 and also by engagement of the bracket 7 with the arms of bracket 13 tending to spread the latter arms apart. The bolts 16 fit loosely through holes in the brackets and permit a limited amount of lengthwise relative movement of the brackets.

The post 14 shown in Figure 4 is of corrugated channel shaped metal preferably set in a concrete footing. It is to be understood however, that any suitable post may be used and set in any suitable manner to afford adequate support for the rail A and its mountings.

When a vehicle strikes the rail A, the individual member 1 so struck is momentarily flexed but almost instantly distributes the impact force to the entire rail A and its end anchors, thus preventing undue bending or a permanent setting of such member 1. If the force is great enough the springs 17 on two or more posts may be compressed. The rail A and springs 17 tend to spring back to their original position and to push the vehicle away from the rail A or, when the blow is delivered at an acute angle, to cause the ve-

hicle to slide along the rail without striking a post. The rigidity of the rail, its tension, and the mountings all co-operate to prevent any twisting or vertical movement which might allow a vehicle wheel to tip the rail and pass under it, thereby becoming locked in place or diverted along the rail until the wheel engages a post.

The corrugated surface of rail A facilitates the sliding of a wheel along the rail and does not mar the vehicle on such a large area as might be the case with a flat rail.

The device practically frees itself of any vehicle which strikes it, and with little or no damage to the vehicle. It does not require any special warning lights because it is self-warning when light strikes its corrugated surface. It is sturdy and yet inexpensive to make, erect and repair.

Having thus described our invention so that those skilled in the art may be able to practice the same what we desire to secure by Letters Patent is defined in what is claimed.

What is claimed is:

1. A rail mounting for a road guard comprising a bracket adapted to be secured to a supporting post and having laterally extending arms, a second bracket loosely sliding against said arms, means uniting said brackets in assembled position, and spring means interposed between said brackets to resist movement of the brackets toward each other.

2. A guard railing of the character described comprising a plurality of posts, a bracket member secured to each post and having outwardly extending arms, a companion member yieldably positioned between said arms and connected to each bracket member and held from vertical movement by said arms, and rail members secured to said companion members.

3. A guard railing of the character described comprising a plurality of posts, a bracket member firmly secured to each post, companion bracket members, bolts loosely connecting a companion member to its bracket member, resilient means interposed between said bracket members and the companion members, and rail members secured to said companion members.

4. A road guard comprising a plurality of corrugated metal rail members secured together in end-to-end relation, supporting means, means for securing said rail members to said supporting means including a movable member secured to each rail member, a fixed member secured to each supporting means, resilient means disposed between the said fixed and said movable members, and means to effect relative movement of adjacent rail members.

5. A road guard of the character described comprising a plurality of posts, a bracket member secured to each post, a companion member yieldably connected to each bracket member and held from vertical movement thereby, and rail members secured to said companion members against relative movement thereto.

6. A highway guard rail comprising a plurality of sheet metal members, each member consisting of an elongated piece of sheet metal having substantially semi-circular longitudinal edge flanges, one end of each member being of a width slightly less than the distance between the flanges at the other end, the narrow end of each member being assembled in telescoping relation within the curved flanges of the adjacent member, and means securing the telescoping ends of the rail members in assembled position.

7. A highway guard rail comprising a plurality of sheet metal members, each member consisting of an elongated piece of sheet metal having curved longitudinal edge flanges on one side thereof, one end of each member being of a width slightly less than the distance between the curved edge flanges of an adjacent member, the narrow end of each member being assembled in telescoping relation within the curved flanges of an adjacent member, means securing the telescoping ends of the rail members in assembled position, and adjusting means attached to the ends of adjacent telescoped members for adjusting the positions of such members with respect to each other and imparting tension to the rail. 5
8. A road guard comprising a plurality of posts fixed in position along the side of a highway, rail supports, including spring means, on the highway sides of the posts and extending outwardly therefrom sufficiently far to prevent contact of vehicle wheels with the posts, a guard rail on the highway sides of the supports in position to engage a wheel hub, the said supports serving to resist resiliently impact forces of a vehicle against the rail, said rail consisting of a plurality of sheet metal members, each member having curved longitudinal edge flanges on one side thereof, the ends of said members being nested and telescoped with the curved flanges of adjacent members, means connecting the rail members together in end to end nested and telescoped position, and means acting independently of the spring means in the rail supports for exerting tension on the rail. 20
9. A road guard comprising a plurality of posts, a rail extending past and supported by a plurality of said posts, adjustable means at the ends of the rail for applying tension thereto, the rail including a plurality of sections, the adjacent ends 25
- thereof disposed in telescoping relation and presenting a substantial uninterrupted vehicle engaging surface and adjusting means at the ends of said sections and wholly to one side of the point of overlap for adjusting the position of the ends 5 of adjacent sections relative to each other. 10
10. In a highway guard a rail of uniform width consisting of a plurality of similar rail members, each member consisting of an elongated piece of sheet metal having the longitudinal edges thereof rearwardly bent to form opposite curved longitudinal edges, one end of each of said members being so formed as to be received and retained between the opposite curved longitudinal edges of an adjacent rail member in telescoping relation 15 and means for connecting the telescoping ends. 15
11. In a highway guard a rail of uniform width consisting of a plurality of similar rail members, each member consisting of an elongated piece of sheet metal having the longitudinal edges thereof rearwardly bent to form opposite curved longitudinal edges, one end of each member being of slightly less outside width than the distance between the curved edges at the other end, the narrow end of each member being assembled in telescoping relation within the curved edges of the adjacent member and means for connecting the telescoping ends. 20
12. A road guard comprising a plurality of posts, a rail extending past and supported by a plurality of said posts, the rail being composed of a plurality of sections overlapping at their ends, and adjusting means secured to two overlapping sections and disposed between the ends of one of said sections and wholly to one side of the point 25 of overlap for adjusting the extent of overlap of said sections. 30
